COMBINED STEAM GENERATOR AND WRINKLE REMOVER FOR DRY CLEANING OR THE LIKE

Nathan M. Weiss, Buena Park, Calif.

Application November 7, 1958, Serial No. 53,298

Term of patent 14 years

(Cl. D49—1)

Fig. 1 is a side elevational view of a combined steam generator and wrinkle remover for dry cleaning or the like showing my new design, the opposite sides of the cylindrical elements being the same.

Fig. 2 is a top plan view thereof.

Fig. 3 is an enlarged front view of the upper portion of the design.

Fig. 4 is a top plan view of the nozzle and support shown in Fig. 3.

The dominant portions of the design are shown in the drawing in full line.

I claim:

The ornamental design for a combined steam generator and wrinkle remover for dry cleaning or the like, substantially as shown and described.
